UNITED STATES PATENT OFFICE.

JOEL ROBINSON, OF LA GRANDE, OREGON.

FOOT-WARMER.

SPECIFICATION forming part of Letters Patent No. 271,364, dated January 30, 1883

Application filed October 7, 1882. (No model.)

To all whom it may concern:

Be it known that I, JOEL ROBINSON, of La Grande, in the county of Union and State of Oregon, have invented a new and Improved 5 Foot-Warmer, of which the following is a full, clear, and exact description.

The object of my invention is to provide a new and improved warming device for vehicles, upon which warming device the feet are to be 10 placed to keep them warm.

The invention consists in the combination and arrangement of parts, substantially as hereinafter more fully set forth.

Reference is to be had to the accompanying 15 drawings, forming a part of this specification, in which similar letters of reference indicate corresponding parts in all the figures.

Figure 1 is a cross-sectional elevation of my improved foot-warmer on line *xx*, Fig. 2. Fig. 20 2 is a sectional plan view of the same on the line *yy*, Fig. 1. Fig. 3 is a plan view of the cotton-holder of the lamp.

The box *A* is formed with a back and front of sheet-iron, and sides *A'* of perforated metal 25 plates or of wire-netting. The front is provided with a vertically-sliding door, *B*; but it can be provided with a hinged door or any other suitable or like device. The box *A* is secured on a base-board, *C*, and the top and 30 back of the box *A* and the top of the base-board *C* are covered by a sheet of copper, *D*, which is riveted to the back of the box *A* and to the top of the base-board. The box *A* and the base-board *C* are so fixed on the bottom of 35 the vehicle that the occupant of the vehicle can place his feet on the base-board *C* and against the back of the box *A*, in which box *A*, I place a lamp, which is provided with a chimney, *E*, made of sheet metal and extending almost to the top of the box. The burner 40 *G* of the lamp is of the usual construction. The lamp *F* is composed of an outer cylindrical vessel, *F'*, open at the top and closed at the bottom, and of an inner cylindrical vessel, *F''*, closed at the top and open at the bottom. The inner cylindrical vessel, *F''*, is provided at its bottom with a series of cross-bars, *H*, which hold a quantity of cotton or other fibrous ma-

terial, *J*, in the vessel *F''*. The cotton or other fibrous material, *J*, prevents the oil from being thrown about in the lamp by the jolting of the vehicle, and prevents the oil from flowing out in case that the lamp is upset, and thus prevents explosions and danger from fire. The hot gases issuing from the top of the chimney 55 *E* heat the top and back of the box *A*, and also heat the copper plate *D*, the radiating heat from which keeps the feet warm. The air for combustion passes into the box *A* through the apertures of the side plates, and 60 the heated air also escapes through the said side plates, and is confined by the blanket usually used by the occupant of the vehicle, and thus assists in keeping the legs and feet of the occupant warm. I use a metal chimney, 65 *E*, as the same is very strong and durable, cannot be broken, and only serves to conduct the heated gases upward, and forms a draft for the flame. A glass chimney would be useless, as the lamp is not used to illuminate, but 70 only to heat.

Having thus fully described my invention, I claim as new and desire to secure by Letters Patent—

1. In a foot-warmer, the combination, with 75 the box *A*, provided with perforated sides, of the base-board *C*, and the sheet of copper attached to the top and back of the box *A* and to the top of the base-board *C*, substantially as herein shown and described, and for the 80 purpose set forth.

2. In a foot-warmer for vehicles and sleighs, the combination, with the box *A*, provided with perforated sides, and the base-board *C*, the top and back of said box and the top of 85 said board being covered by a sheet of copper, of the lamp having an outer vessel, *F'*, closed at the bottom, and an inner vessel, *F''*, open at the bottom and closed at the top, the latter vessel, *F''*, having cross-bars *H* near its bottom, 90 and cotton filling *J*, substantially as and for the purpose set forth.

JOEL ROBINSON.
